(57) **CLAIM**

The ornamental design for a connector for educational construction kits, as shown and described.

DESCRIPTION

FIG. 1 is a front perspective view from above.

FIG. 2 is a rear perspective view from below.

FIG. 3 is a top plan view.

FIG. 4 is a bottom plan view.

FIG. 5 is a front view.

FIG. 6 is a rear view.

FIG. 7 is a left side view.

FIG. 8 is a right side view; and,

FIG. 9 is a section view (9-9 as indicated in FIG. 3).

FIG. 3 shows a dashed line indicating an axis labeled "9" for the section view of FIG. 9. The dashed line and labels indicating the axis form no part of the claimed design.
